UNITED STATES PATENT OFFICE,

MARTHA WASHINGTON, OF PHILADELPHIA, PENNSYLVANIA.

DESIGN FOR A THIMBLE AND SCISSORS CASE.

SPECIFICATION forming part of Design No. 28,175, dated January 18, 1898.

Application filed December 11, 1897. Serial No. 661,565. Term of patent 7 years.

To all whom it may concern:

Be it known that I, MARTHA WASHINGTON, a citizen of the United States, residing in the city and county of Philadelphia, State of Pennsylvania, have invented and produced a new and original Design for a Thimble and Scissors Case, of which the following is a specification, reference being had to the accompanying drawings, forming part thereof.

o The leading feature of my design for a thimble and scissors case is a pouch with jaws at one end thereof and a flap at the other end thereof.

Figure 1 represents a perspective view of a thimble and scissors case embodying my design. Fig. 2 represents a central vertical section thereof on line xx , Fig. 1.

In the drawings, A designates the body of a pouch, at the upper end of which are the jaws B and at the bottom thereof is the flap C. The body is of flaring form, and the jaws and flap are provided with fastenings, respectively D and E.

Having described my invention, what I claim as new, and desire to secure by Letters Patent, is—

The design for a thimble and scissors case, substantially as shown and described.

MARTHA WASHINGTON.
